UNITED STATES PATENT OFFICE

HERMAN SAXON, OF NEW YORK, N. Y.

DESIGN FOR A CASING OF AUTOMOBILE-LAMPS.

No. 39,734.

Specification for Design.

Patented Dec. 29, 1908.

Application filed September 2, 1908. Serial No. 451,459. Term of patent 7 years.

To all whom it may concern:

Be it known that I, HERMAN SAXON, a citizen of the United States, residing at the city of New York, in the State of New York, have invented a new, original, and ornamental Design for a Casing of Automobile-Lamps, of which the following is a specification, reference being had to the accompanying drawing, forming part thereof.

Figure 1 is a side elevation of a lamp casing

showing my new design. Fig. 2 is a front elevation.

I claim:

The ornamental design for casing of automobile lamp as shown.

HERMAN SAXON.
